United States Patent Office.

P. H. MILLS, OF GREEN'S LANDING, MAINE.

Letters Patent No. 82,838, dated September 22, 1868.

IMPROVEMENT IN ROW-LOCKS.

The Schedule referred to in these Letters Patent and making part of the same.

TO ALL WHOM IT MAY CONCERN:

Be it known that I, P. H. MILLS, of Green's Landing, in the county of Hancock, and State of Maine, have invented a new and useful Improvement in Row-Locks; and I do hereby declare that the following is a full, clear, and exact description thereof, which will enable others skilled in the art to make and use the same, reference being had to the accompanying drawings, forming part of this specification, in which—

Figure 1 is a perspective view of my improved row-lock.

Figure 2 is a side view of a portion of the same.

Similar letters of reference indicate like parts.

My invention has for its object to furnish an improved row-lock to receive the oar when rowing, sculling, steering, &c., and hold it securely, while, at the same time, allowing it to be moved freely in any desired direction, and which shall be so constructed as not to be liable to wear or breakage, and will work without clattering, entirely doing away with splitting row-locks, breaking pins, and other annoyances, so common with row-locks constructed in the ordinary manner.

It consists in the row-lock and roller constructed and operating as hereinafter more fully described.

A represents a portion of the side of a boat. B are two ears or supports, attached to the boat. C is a roller, pivoted to and between the ears B. D is the oar-lock or bracket, which receives the oar, and the pin of which enters and works in a hole in the middle part of the roller C, as shown in fig. 2.

In using the row-lock, the smallest part of the oar is placed in the fork of the bracket or lock D, and the oar is then pushed out to the proper distance, and when so arranged it cannot get out by any accident.

Should the boat strike against the wharf, side of a vessel, or other obstruction, all that is necessary to do is to drop the oar, which will then take care of itself, moving freely in any direction.

In case it is desired to have the oar stationary in the row-lock, all that is necessary is to drop a piece of rope-yarn or other soft substance into the oar-lock D before pushing the oar out to its place.

Having thus described my invention, I claim as new, and desire to secure by Letters Patent—

The row-lock D and roller C, constructed and operating in combination with each other, substantially as herein shown and described, and for the purpose set forth.

The above specification of my invention signed by me, this fifth day of June, 1868.

P. H. MILLS.
